UNITED STATES PATENT OFFICE.

ROBERT B. COCHRAN, OF WASHINGTON, NEW JERSEY, ASSIGNOR, BY DIRECT AND MESNE ASSIGNMENTS, TO MORGANS & WILCOX MFG. COMPANY, OF MIDDLETOWN, NEW YORK, A CORPORATION OF NEW YORK.

KNIFE-GRINDER.

1,103,941.

Specification of Letters Patent. Patented July 21, 1914.

Refiling of application Serial No. 491,571, filed April 22, 1909. This application filed April 28, 1914. Serial No. 834,894.

To all whom it may concern:

Be it known that I, ROBERT B. COCHRAN, a citizen of the United States, residing at Washington, in the county of Warren and 5 State of New Jersey, have invented a certain new and useful Improvement in Knife-Grinders, of which the following is a specification.

The invention relates to machines for 10 grinding knives and is intended more particularly for service in grinding the knives of paper-cutting machines while such knives are in position therein, and the object of the invention is to provide a portable machine 15 having easily operated means for securing it removably in position relatively to the knife by engagement with the groove in the cutter table, and in which the grinding disk may be adjusted to the desired angle and 20 held yieldingly against the knife, and revolved by reciprocating the carriage in which the grinding disk is mounted.

The invention consists in certain novel 25 features of construction and arrangement by which the above objects are attained, to be hereinafter described.

The accompanying drawings form a part 30 of this specification and show an approved form of the invention as adapted for operating upon the knife of a paper-cutting machine.

Figure 1 is a plan view of the machine in place on the table of a paper cutter. Fig. 2 is a corresponding front view, a portion of 35 the table being shown in vertical section. Fig. 3 is a plan view of a portion of the table showing the groove and the engaging means therein. Fig. 4 is an end view of the machine with the grinding disk inclined as 40 in service, and showing a portion of the table in transverse section. The remaining figures are on a larger scale. Fig. 5 is a transverse vertical section through the machine and a portion of the knife and table. 45 Fig. 6 is a side elevation of the carriage and its parts alone. Fig. 7 is a corresponding rear view. Fig. 8 is a plan or top view of the same. Fig. 9 is a vertical section 50 through the table and a portion of the machine, with certain parts of the latter in elevation, showing the means for holding the grinding disk at the desired angle.

Similar letters of reference indicate the same parts in all the figures.

The paper-cutting machine may be understood to be of any ordinary or approved type having the usual table M, a vertically reciprocated knife M¹ and groove m in which the edge of the knife is received at the termination of the cutting stroke. The operating and other parts, not shown, may be as usual.

The improved grinding machine has a bar A adapted to lie in the groove m and engage strongly therein by the wedging action 65 of a block B grooved to match to a tapered or inclined feather or rib A¹ on the bar. The latter carries a frame C having at each end a vertical flange or way C¹ curved concavely on its upper face to receive corresponding convex flanges D¹ D¹ on a carrier 70 D and permit the carrier to rotate within prescribed limits upon the curved ways C¹ C¹ in determining its angular position and the parts carried thereon relatively to the 75 knife.

Upward extensions D² from the carrier support a longitudinally extending bar D³ having on its edges straight parallel ways D⁴ D⁴ and a rack D⁵ between such ways; the 80 latter support and guide a traveling carriage F in which is loosely journaled a shaft G carrying a pinion G¹ in mesh with the rack D⁵ and on its inner overhung end an emery wheel N or other grinding disk. The 85 carriage is reciprocated by the hand of the operator upon a handle G² on the upper face of the carriage, and as the pinion is in mesh with the relatively stationary rack D⁵ the reciprocating motion rotates the grinding 90 disk N alternately in opposite directions during the travel. By moving the carrier in the curved ways C¹ C¹ the angle of the face of the grinding disk against the knife may be varied to conform to the bevel forming the cutting edge of the latter, and when thus adjusted is held by clamps E E, one at each end, overlapped upon the curved 95 upper faces of the flanges D¹ D¹ and compressed thereon by bolts E¹ E¹, thus inducing sufficient friction to hold the carrier reliably. The curves of the ways C¹ C¹ are 100 identical and each is an arc of a circle the center of which is shown as lying in the

plane of the knife edge. This arrangement is preferable but may be varied.

A hand lever I fulcrumed on the frame C at I^1 is pivotally engaged at B^1 with the block B and affords conveniently presented means for engaging and disengaging the bar A and block B in the groove m in shifting the machine to a new position along the knife and in removing the machine at the completion of the grinding operation. To permit the frame C to be adjusted relatively to the groove m to insure parallelism of the ways D^4 D^4 with the knife, in case the walls of the groove and face of the knife be not exactly parallel, the attachment of the frame to the bar A is made by means of bolts C^3 C^3 extending through open slots or notches c in the horizontal flanges C^2 C^2 of the frame into the bosses A^2 A^2 at the ends of the bar, thus allowing the frame to be shifted slightly upon the bar at either or both ends as may be required in securing absolute alinement.

The grinding disk is held in yielding contact with the knife by a spring H on the carriage abutting at one end against the head H^2 of a rod H^1 and at the other against a web F^1 on the carriage; the rod extends through the web and through a lever H^3 and is threaded to receive a thumb-nut H^5 by which the tension of the spring may be varied. The lever is pivoted to the carriage at H^4 and its free end impinges against the protruding outer end of the shaft G, thus transferring the force of the spring to the shaft in the direction to move the latter axially toward the knife and hold the face of the disk in yielding contact therewith.

In order to relieve the shaft from the spring pressure when installing the machine, the cam or eccentric J is provided pivotally mounted on the carriage at J^1 and having a handle J^2 by which it may be partially rotated and the swell of the cam thus made to contact with the inner face of the lever H^3 and force it outwardly sufficiently to permit the disk to leave the knife.

At each end of the rack D^5 is a sliding abutment K mounted in ways k k and subject to the force of the springs K^1 K^1 attached at one end to the under face of the abutments and at the other to the under face of the longitudinal bar D³; the function of the abutments is to cushion the carriage at the ends of its reciprocating movements and to prevent the carriage leaving the ways D^4 D^4 .

In the operation of grinding a knife, the stick of wood usually employed to receive the knife edge is removed from the groove m , the cam J turned to retract the grinding disk, and the machine placed on the table M with the locking lever I thrown to the right to move the block B toward the narrow end of the inclined rib A¹ on the bar A; the latter with the block is then inserted in the

groove and the lever thrown to the left to insure strong frictional engagement therewith. The clamps E E are then loosened and the carrier turned on the curved ways C¹ C¹ to present the face of the disk at the proper angle to the bevel of the knife; the clamps are again tightened and the carriage is then traversed along the face of the bevel and if the line of travel is found to be not parallel with the knife the proper adjustment of the frame C on the bar A is made by means of the bolts C³ C³. The cam J is then turned to permit the spring H to act upon the shaft G and the carriage reciprocated with the disk N in contact with the knife until the latter is sufficiently ground. If the knife be longer than the travel of the disk the locking lever is thrown to loosen the bar A and block B and the machine is then shifted and locked in position to treat a new portion of the knife. When the operation is completed the machine is removed without changing its adjustments and may be re-installed when required ready to serve on the same paper cutter without readjustment.

Importance is attached to the features of fastening the machine to the cutter-bed by engagement with the groove therein, and it will be understood that other means than the mechanism shown may be employed for inducing the strong frictional engagement required.

Although the invention is described as applied in sharpening the knives of paper-cutting machines it will be understood that it will serve in other grinding operations to which it may be adapted. Other modifications may be made in the forms and proportions of the parts without departing from the invention, and portions may be used without the whole.

I claim:

1. In a grinding machine of the character set forth adapted to operate upon a knife of a paper-cutting machine, a supporting frame detachably mounted over said machine, grinding mechanism mounted thereon, a bar pendent from such supporting frame and receivable within a groove on the cutting machine frame, and a coöperating member carried by the grinding machine frame and also receivable within said groove, said members having a wedging action and engageable with the walls of said groove for holding the grinding machine in operative relation to the knife.

2. In a grinding machine, a frame, curved ways thereon, a carrier mounted in said ways and movable thereon to vary its vertical angular position relatively thereto, a carriage mounted on said carrier and movable longitudinally thereof, a shaft journaled in said carriage, a grinding disk on said shaft, a rack on said carrier, a pinion

on said shaft in mesh with said rack, and means for holding such machine in operative relation to a knife to be ground.

3. In a grinding machine, a frame, curved ways thereon, a carrier mounted on said ways and movable thereon to vary its vertical angular position relatively thereto, means for holding said carrier in such angular position, a carriage mounted on said carrier to reciprocate thereon, a shaft journaled in said carriage with freedom to move axially, a grinding disk on said shaft, a rack on said carrier, a pinion on said shaft in mesh with said rack, means for holding such machine in operative relation to a knife to be ground, and means for presenting said disk in yielding contact with such knife.

4. In a grinding machine, a frame, curved ways thereon, a carrier mounted on said ways and movable thereon to vary its vertical angular position relatively thereto, means for holding said carrier in such angular position, a carriage mounted on said carrier to reciprocate thereon, a shaft journaled in said carriage with freedom to move axially, a grinding disk on said shaft, a rack on said carrier, a pinion on said shaft in mesh with said rack, means for holding such machine in operative relation to a knife to be ground, means for presenting said disk in yielding contact with such knife, and adjustable means for varying the force of such yielding contact.

5. In a portable grinding machine adapted to operate upon the knife of a paper-cutting machine, a bar having an inclined face, a block having an oppositely inclined face, said bar and block adapted to be received in the groove of said paper-cutting machine, means for moving said bar and block relatively to each other to engage or disengage said groove, and grinding mechanism carried by said bar.

6. In a portable grinding machine, adapted to operate upon the knife of a paper-cutting machine, a bar having an inclined face, a block having an oppositely inclined face, said bar and block adapted to be received in the groove of said paper-cutting machine, means for moving said bar and block relatively to each other to engage or disengage said groove, a frame mounted on said bar, means for adjusting said frame horizontally relatively to said bar, a carrier on said

frame, means for adjusting said carrier angularly on said frame, longitudinal ways on said carrier, a carriage slidably mounted on said ways, and a grinding disk supported in said carriage and rotated by the reciprocations of the latter.

7. In a grinding machine, a frame, curved ways thereon, a carrier movable angularly on said ways, clamps for holding said carrier in the desired angular position, longitudinal ways on said carrier, a carriage mounted on such carrier to be reciprocated along said longitudinal ways, yielding abutments at the ends of said carrier to cushion the impact of said carriage, a shaft journaled in the latter, a rack on said carrier, a pinion on said shaft in mesh with said rack, and a grinding disk on said shaft.

8. In a grinding machine of the character set forth, a carrier having ways parallel with the knife to be ground, a carriage mounted on said ways and arranged to be reciprocated thereon, a shaft journaled in said carriage with freedom to move axially therein, a grinding disk on said shaft, a rack on said carrier, a pinion on said shaft in mesh with said rack, a lever pivotally mounted on said carriage, a spring acting upon said lever to force the latter against the end of said shaft, and means acting in opposition to the force of said spring to relieve said shaft from such spring pressure.

9. In a grinding machine of the character set forth, a bar adapted to engage the groove of a paper cutting machine, a frame supported on said bar, and adjusting means for varying the horizontal angle of said frame relatively to said bar, curved ways on said frame, a carrier mounted on such ways and movable thereon to vary its vertical angle relatively thereto, means for holding said carrier in the desired position, a reciprocating carriage on said carrier, a shaft journaled in said carriage and rotated by such reciprocations, and a grinding disk on said shaft.

In testimony that I claim the invention above set forth I affix my signature, in presence of two witnesses.
